REMOVAL OF COMBUSTION CHAMBER DEPOSITS
BY SOLVENT SPRAYING

Arthur R. Klingel, Jr., Chagrin Falls, Ohio, assignor to
The Standard Oil Company, Cleveland, Ohio, a cor-
poration of Ohio

No Drawing. Application October 19, 1951,
Serial No. 252,207

2 Claims. (Cl. 134—22)

The present invention relates to the removal of undesirable deposits from the combustion chamber of an internal combustion engine, such as the deposits on the tops of automotive pistons.

Such combustion chamber deposits are known to be a factor in engine knocking. Their removal is known to be desirable but this has been difficult. One method that has been proposed is the use of solvents but this presents troublesome problems of removal inasmuch as common methods of applying solvents to remove them, such as with a brush, by dipping or soaking, are quite inadequate. Some of the proposed solvents, for example, caused the deposit to swell thereby sealing more tightly the pores or interstices of the deposited material to retard further the penetration and effectiveness of the solvent.

However, regardless of the type of solvent employed, there is always some softening or loosening of the surface portions of the deposits when it is brushed on, or the coated article is dipped or soaked in the solvent. This indicates that the choice of a particular solvent is not critical. It would further seem to indicate that inability of the solvent to remove the deposits completely is due to poor solvent penetration into the deposit.

It has now been found that such deposits may be efficiently and completely removed by spraying a suitable solvent onto the deposit-covered engine parts in such a manner that the solvent particles will be certain to penetrate and saturate the deposits. Any type of spray apparatus which will atomize the solvent and which will impart high penetration power to such atomized or finely divided solvent particles can be used in my invention.

It is an object of the present invention to provide an efficient method which utilizes any type of engine deposit solvent for removing engine deposit from the various parts of an internal combustion engine.

Other objects and advantages will be more apparent as the invention is described in detail below.

According to the present invention, there are three factors which must be present in order to achieve successful combustion chamber deposit removal. First, the solvent leaving the spraying apparatus must be thoroughly atomized, i. e., the size of the particles ejected from the sprayer must be of such small diameter to insure that they can move through the skin of the carbon deposits. Second, the velocity or force with which the atomized particles are impinged or sprayed onto the engine deposit must be of such extent to insure that the atomized particle will penetrate the skin of the deposit. Third, a solvent suitable for engine deposit must be employed. A series of tests was performed to demonstrate the importance of these factors and such tests will be described later.

Without in any way limiting the present invention, the following theory is offered to explain the operability of the invention. Engine deposit removal by solvent application has been unsuccessful heretofore because the solvent is unable to permeate and saturate the deposit. However, if the solvent can pass into the interstices between the particles of engine deposit, it then can saturate the deposit and dissolve the binder holding the deposit together. By spraying finely divided solvent particles at high velocity onto the engine deposit, the solvent will pass through interstices of the deposit and dissolve the binder so that portions of the deposit can disintegrate.

In carrying out the invention, any type of spraying

apparatus is effective as long as it gives spray of the required type, i. e., one which will penetrate and saturate the engine deposits. For example, a fuel injector such as the type employed in diesel, aircraft, automotive and stationary engines would be quite suitable for the purposes of this invention.

As stated above, the success of the method of this invention depends in part upon the fact that the sprayed solvent particles are finely divided or atomized. The extent of atomization requisite to engine deposit removal may be described in terms of the size of the sprayed solvent particles.

The desired drop size in the spray may be obtained in any manner known in the art. In general, increase of ejection pressure will diminish the mean drop size of the particles thus allowing the sprayed drops to penetrate the engine deposit skin more easily.

Moreover, homogeneity of drop size may also be attained by decreasing the orifice diameter of the spraying device. This results in producing more small type drops, although the size of the smallest drops may be further diminished.

For the purposes of this invention, any spray which has an average particle size (diameter) not greater than about 0.0025 inch will be suitable.

The velocity and thereby the force of the atomized particles is also a function of the ejection pressure, also making higher pressures desirable. The pressure then and the size of the particles of solvent must be coordinated in such a way that the atomized solvent will penetrate the skin and body of the encrusted deposit. Ordinarily improvements in the one factor will follow improvements in the other factor. Thus an increase in pressure will improve the size and homogeneity of the particles and will also increase the velocity and penetration of the atomized particles of solvent.

Any engine deposit solvent may be employed. Examples of such solvents are well known and include alcohols, ketones, organic acids, esters, ethers, organic halides, hydrocarbons and amines. The aromatic amines are particularly good solvents for resinous materials. More preferably, pyridine, quinoline, picolene and commercial coal tar bases are desirable. Furthermore, a polyfunctional solvent (one in which several organic groups such as ether and alcohol groups are combined in the solvent molecule) has much greater solvent power than mixtures of mono-functional solvents. In addition, ammonium compounds such as ammonium chloride, ammonia, tetramethyl ammonium hydroxide, ammonium acetate or polysulfide are effective solvents for attacking the engine deposits having lead compounds therein. Many of such solvents have been proposed and any may be used which has a softening or disintegrating action on the deposit. The invention is not concerned with the use of any particular type of solvent, but rather with a novel method of applying liquids which have a solvent action on the deposit.

The following examples are illustrative of solvents which are available for use in the method of the invention: carbon tetrachloride (Pat. No. 1,386,385); selenium oxychloride (Pat. Nos. 1,473,350 and 1,445,329); alkaline organic compounds such as a mixture of aniline, ethyl alcohol, benzol and naphthalene (Pat. No. 1,786,860); aliphatic amines (Pat. No. 1,787,789); cyclic alcohols such as benzyl alcohol with benzol and ethyl alcohol (Pat. No. 1,820,395); oxazines such as morpholines alone or with benzol and alcohol (Pat. No. 1,833,429); aliphatic amides such as diethyl formamide (Pat. No. 1,924,722); unsaturated aliphatic ethers such as allyl ethyl ether (Pat. No. 1,925,732); an aliphatic diamine and a pyridine compound such as ethylene diamine and pyridine (Pat. No. 1,934,076); terpene hydrocarbons such as carvone (Pat. No. 1,936,681); derivatives of furfuryl alcohol such as methyl furoate (Pat. No. 1,936,682); orthodichloro-benzene, triethanolamine and oleic acid (Pat. No. 2,006,636); onium base compounds such as tetramethyl ammonium hydroxide (Pat. No. 2,047,191).

A series of tests, which are described below, was carried out to show the necessity of employing an atomized

solvent spray at high velocity to effect engine deposit removal.

Test 1

In order to determine the effect of a solvent on engine deposit, an automotive piston top containing a typical combustion chamber deposit thereon was dipped into one pint of a commercial coal tar base solvent as proposed for this purpose. After an extended period of time the piston top was removed from the solvent and it was noted that the engine deposit had softened but that scraping with a chisel was still necessary for removal thereof. This test demonstrated that engine deposit removal from engine parts cannot be accomplished by merely soaking in a solvent. This test was repeated with all solvents available on the market for this purpose and none removed the deposit completely.

Test 2

In order to ascertain the role that a high velocity stream might play in engine deposit removal, an automotive piston top having engine deposit thereon was treated with one pint of water which was ejected at a pressure of 2500 pounds per square inch from an orifice having a diameter of .013 inch. The water was not atomized but only ejected as a high velocity stream. After such treatment, the piston top was examined and it was found that none of the engine deposit had been removed. This demonstrates that engine deposit removal cannot be attained by the sole employment of a high velocity. This test shows that it is not merely the force of a high-speed liquid, which might be regarded as analogous to an abrasive, that removes the deposit.

Test 3

In order to determine the combined effect of a solvent and a high velocity stream on engine deposit, an automotive piston top having engine deposit thereon was treated in accordance with the procedure used in Test 2. However, this time one pint of the commercial coal tar base solvent employed in Test 1 was used on the engine deposit. After such treatment, it was noted that the deposit on the piston top was softened but that it had not been removed by this method of treatment. This test indicates that solvent and high velocity treatment combined are insufficient to remove engine deposits from engine parts.

Test 4

In this test, all three factors of atomization, high velocity and presence of solvent were combined. Less than 0.25 cc. of the same commercial coal tar base employed in Tests 1 and 3 were sprayed onto the top of an automotive piston having engine deposit thereon. This solvent was sprayed in atomized form and at a pressure of 2500 pounds per square inch from an injection nozzle designed for use as a fuel injector in a diesel engine. The injector had an orifice diameter of .04 inch. The size of the solvent particles were within the usual range of such atomized sprays.

After the above test was performed, the piston top was examined and it was found that the engine deposit which had been directly struck by the sprayed particles was completely removed so that the metal of the piston top was bared. The results of all the above tests demonstrate that engine deposit removal can be accomplished by spraying onto the deposit an atomized solvent at high velocity.

Although in Tests 2, 3 and 4 a pressure of 2500 pounds per square inch was employed, it is not intended that this be the only pressure for ejecting atomized spray. The velocity necessary to cause a sprayed particle to penetrate engine deposit will depend, of course, on the type of deposit to be removed. The average velocity of the particles and the uniformity of size of the particles increase with an increase in spraying pressure. The mean size of the particles decreases with an increase in spraying pressure. To remove engine deposits by the method of this invention, the average velocity of the particles should be at least the average velocity obtained with a spray pressure of not less than 1000 pounds per square inch.

For purposes of this invention, the term "atomized particles" is defined as particles having a diameter not greater than 0.0025 inch.

Although the invention has been described with particular reference to the foregoing tests and illustrations, such tests and illustrations are not to be construed as limiting the scope of the invention except as defined in the claims.

I claim:

1. A method for removing engine deposits from the parts of an internal combustion engine comprising spraying said deposits under pressure with a solvent therefor, said solvent spray being in the form of atomized particles having an average particle size of not over about 0.0025 inch and an average velocity obtained by an atomizing pressure of not less than 1000 pounds per square inch, whereby the deposit is removed by said spray.
2. A method for removing engine deposits from the parts of an internal combustion engine comprising directing a jet of an atomized spray of solvent for said deposits against the deposits, said atomized spray having an average particle size of not over about 0.0025 inch and an average velocity obtained by an atomizing pressure of not less than 1000 pounds per square inch.
